LAVATORY SEAT

Ricardo Blackburn, Heidelberg, Victoria,
AustraliaApplication December 16, 1949, Serial No. 133,242
In Australia November 15, 1949

3 Claims. (Cl. 4—235)

1

This invention relates to lavatory seats of the kind which are normally adapted for use by adults but are capable of adjustment so that they may be used by children.

Hitherto such adjustable seats have not proved to be entirely satisfactory in that the child user had necessarily to assume an unnatural sitting attitude which had the effect of causing a feeling of insecurity and undesirable tension particularly in the leg and stomach muscles.

The primary object of the present invention is to provide an improved lavatory seat of the kind indicated which is designed to overcome the aforesaid objections and enable the child user to assume a desirable relaxed posture.

The improved seat is of relatively simple and inexpensive construction, easily cleaned when required and capable of being readily fitted to existing toilets.

Referring to the drawings which form part of this specification:

Figure 1 is a perspective view of a lavatory seat in accordance with a preferred embodiment of the present invention.

Figure 2 is a longitudinal section of the improved seat.

Figure 3 is a fragmentary plan view, on an enlarged scale, of one of the hingeable connections seen in Figure 1.

Figure 4 is a sectional elevation of the parts seen in Figure 3 but with an adjustable portion of the seat occupying its raised position.

In accordance with the present invention, the improved seat may be of substantially annular formation and incorporates front and rear portions. The front portion consists of upper and lower sections 2 and 3 respectively, the lower section being fixed to or formed integral with the rear portion 4 whilst the upper section is hingeably connected to the rear portion of the lower section so as to be capable of being swung upwardly and backwardly in relation to its associated lower section.

The parts forming the complete seat may as usual be adapted to be hinged as at 6 to a wall 7 or any other suitable support so as to rest upon the top of a lavatory bowl 8. In order to minimize the risk of breakage the seat is preferably provided on the lower surface with a plurality of shock absorbers 9 which may consist of rubber or any other suitable resilient material.

The combined thickness of the associated upper and lower sections is predetermined so that when the sections are arranged in over-

2

ing relationship the upper surface of the upper section is substantially flush with the upper surface of the rear portion 4 and thus forms a seat for an adult.

Where the rear portion of the seat merges with the lower section 3, transverse stepped shoulders 11 are formed at opposite sides of the central aperture 12 in the seat. As seen in Figures 3 and 4 part of the cross sectional formation of these shoulders is complementary to the cross sectional formation of the rear ends of the upper section so as to form a desirable close fit therewith when the upper section occupies its lowered position.

Any suitable means may be employed for hingeably connecting the upper section 2 to the rear portion 4 of the seat. For example, this hingeable connection may consist of interfitting apertured lugs 13 on the upper section and rear portion of the seat and a pair of co-aligned pivot pins 14 adapted to interengage said lugs. These pins are preferably readily removable so that the upper section of the seat may be detached periodically for cleaning purposes.

Means are provided for limiting the backward swinging movement of the upper section. For example, transverse limit stops 16 may be provided on the lower section in the path of the apertured lugs on the upper section so that the last mentioned lugs will engage the limit stops and hold the upper section in the desired raised position when so desired. The aforesaid stepped shoulders also preferably act as limit stops so as to provide a firm support for the upper section when occupying its raised position for a child user.

The upper section 2 of the seat is also preferably provided with a pair of arm rests 17 so as to provide a feeling of added security for a child. These arm rests may be fixed or detachably connected in any suitable manner to the bottom of the upper section and spaced apart so as to clear the lower section 3 when the upper section is swung down into engagement therewith. In order to minimise noise and avoid damage the upper section is preferably provided with a rubber or any other suitable shock absorbing pad 18 as seen in Figures 1 and 2.

As usual, a seat cover 21 of any suitable form is preferably hinged to the rear portion 4 as at 22 so as to conceal the central aperture 12 when the seat is not in use.

It will be apparent from the foregoing that the improved construction provides in effect, two superimposed seats, the upper seat being adapted

for use by adults whilst the lower seat is specially designed to meet the requirements of children. To specifically adapt the lower seat for children, the width and cross-sectional area of the lower section 3 is less than that of the upper section 2, as clearly indicated in Figures 1 and 2, so as to more readily fit the legs of a child. When required the seat may be readily converted for use by children simply by swinging the upper section 2 into its upright operative position as in Figures 1 and 2 which has the effect of uncovering the lower section 3 forming the child's seat and providing a convenient back-rest for the user.

The improved seat may be composed of synthetic resin, wood or any other suitable material.

Various alterations, modifications and/or additions may be introduced into the foregoing construction and arrangement of parts without departing from the ambit of the invention as defined by the appended claims.

Having now described my invention, what I claim as new and desire to secure by Letters Patent is:

1. A combined adult and child's toilet seat comprising a rear portion and a front portion, the front portion including a lower section forming a child's seat and which is rigidly fixed with the rear portion and an upper section pivotally mounted at the rear upon said rear portion so as to overlie the lower section in complementary relationship with the rear portion to form a toilet seat for an adult, and limit stops on the lower section engageable by said upper section when said upper section is pivoted upwardly for limiting upward and backward swinging movement of said upper section to form a backrest for a child seated on the lower section, the width and cross sectional area of said lower section being less than that of said upper section so as more readily to fit the legs of a child.

2. A device according to claim 1 wherein said lower section and said rear portion are integral, and have transverse stepped shoulders at opposite sides of the seat where said rear portion merges with said lower section, said shoulders being complementary to the rear ends of said upper pivoted section.

3. A combined adult and child's toilet seat comprising a rear portion and a front portion, said front portion including upper and lower sections of such predetermined thickness that when arranged in overlying relationship the upper surface of said upper section is substantially flush with the upper surface of said rear portion so as to form a toilet seat for an adult, said rear portion being integral with said lower section with transverse stepped shoulders therebetween, said shoulders being complementary to the rear ends of said upper section, a hingeable connection between said upper section and said rear portion, including interfitting apertured lugs on both said upper section and said rear portion and a pair of co-aligned removable pivot pins interengaging said lugs, the width and cross sectional area of said lower section being less than that of the upper section, and limit stops on said lower section in the path of the lugs on said upper section for limiting the pivoting of the upper section to form a backrest for a child seated on the lower section.

RICARDO BLACKBURN.
